CLAIM

The ornamental design for a knee brace, as shown and described.

DESCRIPTION

FIG. 1 is a perspective view of an elbow brace, showing our new design, in use condition.

FIG. 2 is a front elevational view of the knee brace of FIG. 1.

FIG. 3 is a side elevational view of the knee brace of FIG. 1.

FIG. 4 is a rear elevational view of the knee brace of FIG. 1.

FIG. 5 is a bottom view of the knee brace of FIG. 1; and, FIG. 6 is a top view of the knee brace of FIG. 1.

The broken line showing in FIG. 1 is for illustrative purposes only and forms no part of the claimed design.
